UNITED STATES PATENT OFFICE

2,463,361

ADJUSTABLE BEAM LIGHT

Ernesto Cardona de la Parra, Mexico City, Mexico, assignor of one-tenth to Triangle Engineering Products Co., Inc., Philadelphia, Pa., a corporation of Pennsylvania

Application November 9, 1945, Serial No. 627,550
In Mexico October 8, 1945

7 Claims. (Cl. 240—46.03)

1

This invention relates to vehicle headlights. An object of this invention is to provide a headlight structure embodying a casing having a lens and a light bulb with means between the lens and the light bulb for regulating the projection of light rays.

Another object of this invention is to provide an improved headlight which is formed with a pair of selectively movable shields whereby certain of the light rays may be cut off so as to regulate the projection of the rays.

A further object of this invention is to provide a headlight which includes means for projecting the light rays forwardly, and also means for projecting the light rays laterally so as to illuminate the side of the road.

A further object of this invention is to provide a headlight embodying one or more light ray deflecting members movably mounted in the casing which are selectively adjustable by remotely disposed means connected to the deflecting members.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a detail side elevation of a headlight constructed according to an embodiment of this invention,

Figure 2 is a detail front elevation of the device, Figure 3 is a longitudinal section taken vertically through the device,

Figure 4 is a sectional view taken on the line 4—4 of Figure 3,

Figure 5 is a sectional view taken on the line 5—5 of Figure 3,

Figure 6 is a fragmentary sectional view taken on the line 6—6 of Figure 4,

Figure 7 is a fragmentary sectional view taken on the line 7—7 of Figure 4,

Figure 8 is an exploded fragmentary side elevation of one of the deflectors and guide therefor,

Figure 9 is a fragmentary sectional view taken on the line 9—9 of Figure 3,

Figure 10 is a detail front elevation of the inner lens structure, and

Figure 11 is a diagrammatic view showing the positions of the movable deflectors.

Referring to the drawings the numeral 15

2

designates generally a casing which includes a forward casing member 16, an intermediate casing member 17 and a rear casing or reflector member 18. The forward casing 16 includes a frusto-conical body 19 having the smaller end thereof foremost, which is formed with a forward annular flange 20 and a rear annular flange 21.

An outer lens 22 is disposed against the flange 20 being secured against the flange 20 by means of a ring-shaped channelled clamping member 23, which is split at its lower portion and formed with a pair of ears 24 secured together by fastening means 25. The flange 20 and the outer margin of the lens 22 are seated in the channel formed by the ring 23 so that when the latter is in applied position the lens 22 will be removably secured to the forward end of the forward housing 19. An inner lens assembly, generally designated as 26, is disposed inwardly of the lens 22 and comprises a disc-shaped plate 27 which is formed with a central opening 28 within which a magnifying lens 29 is positioned, the lens 29 being secured within the opening 28 by means of a crimped bezel 30 which supports the lens 29 and clamps the plate 27 about the margin of the opening 28. The lens 26 is seated in a channelled bezel 31 which has secured thereto a plurality of inwardly or rearwardly projecting lugs 32 formed with elongated slots 33. The inner surface of the forward housing member 16 has secured thereto inwardly offset bars 34 through which fastening members 35 extend for adjustably supporting the lens 26 within the housing 16.

A cushioning ring member 36 is secured to the forward side of the bezel 31 extending radially outwardly therefrom and engaging against the inner surface of the housing 16, so as to firmly seal the lens 26 relative to the housing 16. As shown in Figure 10 the lens structure 26 includes a non-transparent lower portion 37 of substantially semi-circular configuration and a transparent upper portion 38 which may be suitably colored and in the present instance is colored green. The transparent upper portion 38 may also be of translucent material so as to deflect any light rays emanating from the light source, whereas the direct light rays and reflected light rays reflected from the reflector 18 passing substantially axially through the lens member 27 are adapted to pass through the central lens 29. In order to provide for holding any upwardly directed light rays from passing through the lower portion 37 of the lens 27 I have provided a substantially semi-circular metal plate 39, which

bears against the inner side of the plate 21 and is seated within the bezel 31.

The rear housing 18 includes a concavo convex reflecting member 40 which is formed with a marginal flange 41 and is also formed centrally thereof with a sleeve 42 on the outer convex side within which a light bulb socket 43 is positioned being adjustably secured therein by means of a set screw 44. The inner concave parabolic surface of the concavo convex member 40 is formed with a reflecting characteristic for reflecting the light rays from a light bulb or light source 45 engaging in the socket 43. The intermediate housing 17 includes a frusto-conical body 46 having the larger end thereof foremost and provided with a flange 47 confronting the rear flange 21 of the forward housing 16. The rear end of the body 46 is provided with an annular flange 48 confronting the flange 21 and a split ring-shaped coupling member or clamping ring 49 secures the two flanges 41 and 48 together, so as to support the reflector member 18 axially of the intermediate housing member 17. A disc-shaped plate 50 is positioned between the two housing members 16 and 17 being positioned at its marginal portions between the two flanges 21 and 47. The two flanges 21 and 47 are removably clamped together by means of a split ring-shaped channel member 51. The plate 50 is formed with a substantially semi-circular opening 52 having the straight edge 53 thereof positioned slightly above the axial center of the plate.

The remaining portion 54 of the plate is lowest and provides a deflector or baffle for preventing any light rays from the upper portion of the reflector 40 from being directed forwardly and downwardly through the lens members 22 and 26. The plate 50 has positioned on the forward side thereof a substantially semi-circular deflector or ray cut off member 55 which is pivotally mounted on a pivot 56 extending through the deflector 55 and through the plate 50. The plate 50 is formed with a pair of stop members 57 and 58 spaced circumferentially from each other about the margin of the opening 52, so as to limit the turning or swinging movement of the plate 55. The stop members 57 and 58 are provided with resilient cushioning members 59 and 60 for engagement with lugs 61 and 62 respectively when the plate 55 is turned in order to eliminate any noise caused by turning of the plate 55. Normally the plate 55 is disposed in inoperative position, as shown in Figure 5, with the lug 62 engaging the cushion member 60 of the stop member 58. A segmental guide member 63 is fixed to the rear end portion of the housing 16 and provides a guide means for guiding the plate 55 as it is adjusted about the pivot member 56. In order to provide for the adjustment of the plate 55 relative to the opening 52, I have provided a flexible operator 64 connected at one end to an offset pivot member 65 fixed to the plate 55. The operator 64 may be extended to a suitable position, such as to a point within the body of the vehicle or may be either manually or otherwise actuated, so as to provide for the adjustment of the plate 55.

The plate 50 has slidably mounted on the rear side thereof a second deflector plate 66. The plate 66 has a straight upper edge 67 parallel with the straight edge 53 of the opening 52 and the plate 66 is slidably mounted in pairs of guide members 68 and 69 which are fixed to the rear side of the plate 50. A pair of stop members 70 are secured to the rear side of the plate 50 above

the straight edge 53 and limit the upward movement of the plate 66. The plate 66 is vertically moved to either operative or inoperative position by means of a rockable lever 71. The lever 71 includes a substantially U-shaped member 72 having a straight extension 73 extending from one leg thereof and the lever 71 is rockably mounted on a pivot member 74 secured to the plate 50. The plate 66, as shown in Figure 9, is formed with elongated slot 75 so that the plate may be vertically moved with rocking of the lever 71. The opposite leg of the U-shaped member 72 is formed with an elongated opening 76 within which a pin 77 fixed to the plate 66 is adapted to loosely engage. The lever 71 is adapted to be rocked by endwise movement of a flexible operator 78 which may be in the form of Bowden wire, which is fixed, as at 79, at one end thereof to the lever 71 and extended to a remote position, such as to a point within the body of the vehicle. The operator 78 may be either manually, electrically or otherwise operated as may be desired.

In the use and operation of this headlight under normal driving conditions the headlight may be used with the deflectors 55 and 66 in an inoperative position. When it is desired to cut off any portion of the light rays on one side of the road, the deflector 55 may be rotated, such as to a position shown by the dotted lines in Figure 5. In this latter position the deflector 55 leaves fully a quarter of the lenses open for the passage of light rays therethrough. The intermediate housing member 17 is provided in the side thereof with a transparent window 80, which is adapted to provide for the projection of light rays laterally of the headlight for lighting up the outer edge of or side of the road. In the event it is desired to deflect the light beams passing through the lenses these beams may be deflected by vertically raising the vertically movable deflector 66. When the upper edge 67 of the deflector 66 rises above the straight edge 53 of the plate 50 the light rays passing outwardly and upwardly will be cut off so that only the downwardly directed light rays lighting up the road for a relatively short distance in front of the headlight will be projected through the lenses of the headlight. In order to provide for the proper positioning of the plate 50 with the deflectors mounted thereon between the two housing members 16 and 17, I have provided a pair of positioning pins 81, which are carried by the flange 21 and which engage in openings 82 formed in the outer portion of the plate 50.

This light controls the rays of light with the help of a reflector which can be used in any size or form as the need requires. This result can be achieved by the interception of the light rays which in turn can be used according to the purpose for which the light is to be employed as in the drawings of this application. This light is obtained through an interception between the reflector and the lens through which the light has to pass, and the interceptor can be adjusted for any distance, size, form or need. This light can be made into all forms for any commercial uses and can be employed for ballrooms, theatres, landing fields, interior lighting, street lamps or any other industries where a strong light is necessary, without ruining the sight of the employees.

The exact configuration illustrated is regarded as the optimum, but some of the desirable results inherent in this disclosure may be obtained by various slight modifications including some departure from the exact configuration shown, and

it is therefore requested that the scope of the invention should be regarded as limited only by the terms of the claims.

What I claim is:

1. In a light having a casing, a light source and a lens; deflector means in the casing comprising a disc-shaped plate disposed transversely across said casing and having a substantially semi-circular opening in the upper portion thereof, the diameter of said opening extending horizontally across said casing, a deflector plate having a straight upper edge, means movably supporting said deflector plate from said first plate, and means for moving said deflector plate to thereby vary the size of said opening.

2. In a light having a casing, a light source and a lens; deflector means in the casing comprising a disc-shaped plate disposed transversely across said casing and having a substantially semi-circular opening in the upper portion thereof, the diameter of said opening extending horizontally across said casing, a semi-circular deflector disposed on one side of said plate, means pivotally mounting said deflector on said plate, and means for adjusting said deflector to thereby vary the size of said opening.

3. In a light having a casing, a light source and a lens; deflector means in the casing comprising a disc-shaped plate disposed transversely across said casing and having a substantially semi-circular opening in the upper portion thereof, the diameter of said opening extending horizontally across said casing, a vertically movable deflector at one side of said plate, means slidably mounting said deflector on said plate, a deflector operating lever pivotally carried by said plate and connected to said deflector, and operating means connected to said lever.

4. In a light having a casing, a light source and a lens; deflector means in the casing comprising a disc-shaped plate disposed transversely across said casing and having a substantially semi-circular opening in the upper portion thereof, the diameter of said opening extending horizontally across said casing, a semi-circular deflector disposed on one side of said plate, means pivotally mounting said deflector on said plate, means for adjusting said deflector to thereby vary the size of said opening, a vertically movable deflector, means slidably mounting said latter deflector, a rock lever pivotally carried by said plate and connected to said latter deflector, and operating means for said rock lever.

5. A light comprising a pair of abutting casing members, means securing said members together, a lens closing the forward end of one of said

members, a reflector closing the rear end of the other of said members, a disc interposed between said members having a semi-circular opening in the upper portion thereof, movable deflector means carried by said disc, and means for moving said deflector means to thereby vary the size of said opening.

6. In a headlight having a casing, a light source and a lens; deflector means in the casing comprising a disc-shaped plate disposed transversely across said casing and having a substantially semi-circular opening in the upper portion thereof, the diameter of said opening extending horizontally across said casing, a semi-circular deflector distending horizontally across said casing, a semi-circular deflector disposed on one side of said plate, means pivotally mounting said deflector on said plate, means for adjusting said deflector to thereby vary the size of said opening, a vertically movable deflector, means slidably mounting said latter deflector, a rock lever pivotally carried by said plate and connected to said latter deflector, operating means for said rock lever, and a magnifying lens between said first lens and said defectors.

7. In a headlight having a casing, a light source and a lens; deflector means in the casing comprising a disc-shaped plate disposed transversely across said casing and having a substantially semi-circular opening in the upper portion thereof, the diameter of said opening extending horizontally across said casing, a semi-circular deflector disposed on one side of said plate, means pivotally mounting said deflector on said plate, means for adjusting said deflector to thereby vary the size of said opening, a vertically movable deflector, means slidably mounting said latter deflector, a rock lever pivotally carried by said plate and connected to said latter deflector, operating means for said rock lever, a magnifying lens between said first lens and said defectors and means slidably supporting said magnifying lens in said casing.

ERNESTO CARDONA DE LA PARRA.
